(57) **CLAIM**

The ornamental design for a shade sail with lights, as shown and described.

DESCRIPTION

FIG. 1 is a front, bottom and left side perspective view of a shade sail with lights showing my new design;

FIG. 2 is a rear, top and left side perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is an enlarged view of portion 9 in FIG. 1;

FIG. 10 is an enlarged view of portion 10 in FIG. 2; and,

FIG. 11 is an enlarged view of portion 11 in FIG. 2.

The dotted lines shown on the shade sail with lights depict stitching that form no part of the claimed design. The broken lines show the features of the shade sail with lights that form no part of the claimed design. The dash-dot-dash broken lines define the boundary of enlarged views and form no part of the claimed design.

1 Claim, 11 Drawing Sheets
